[57] **CLAIM**

The ornamental design for a combined miter fence and box joint fixture, as shown and described.

DESCRIPTION

FIG. 1 is a perspective showing a first side of a combined miter fence and box joint fixture according to the present invention;

FIG. 2 is a perspective view showing the combined miter fence and box joint fixture according to the invention with one of the end caps removed;

FIG. 3 is another perspective view showing the combined miter fence and box joint fixture according to the invention as seen from a second side;

FIG. 4 is a perspective view similar to that shown in FIG. 3 depicting an end cap extended out from one end of the main body of the fence;

FIG. 5 is a perspective view of an alternate embodiment of the combined miter fence and box joint fixture, which includes a clamp; and,

FIG. 6 is a perspective view of the invention showing the aesthetic shape assumed when the combined miter fence and box joint fixture of FIG. 1, in its box joint fixture configuration.

The appearance of the bottom of combined miter fence and box joint fixture forms no part of the claimed design.

The broken line portions of the disclosure are for illustrative purposes only and form no part of the claimed design.

1 Claim, 6 Drawing Sheets

FIG. 2
